(57) **CLAIM**

The ornamental design for a soleplate for clothing iron as shown and described.

DESCRIPTION

FIG. 1 is a front top perspective view of an ornamental design for a soleplate for clothing iron according to the present invention;

FIG. 2 is a front bottom perspective view of the soleplate for clothing iron of FIG. 1;

FIG. 3 is a front elevational view of the soleplate for clothing iron of FIG. 1;

FIG. 4 is a rear elevational view of the soleplate for clothing iron of FIG. 1;

FIG. 5 is a left side elevational view of the soleplate for clothing iron of FIG. 1;

FIG. 6 is a right side elevational view of the soleplate for clothing iron of FIG. 1;

FIG. 7 is a top plan view of the soleplate for clothing iron of FIG. 1; and,

FIG. 8 is a bottom plan view of the soleplate for clothing iron of FIG. 1.

The broken lines shown in FIGS. 1-8 are for the purpose of illustrating environmental structure and form no part of the claimed design.

1 Claim, 8 Drawing Sheets
